(57) **CLAIM**

We claim the ornamental design for a sealing element for a vehicle canopy or the like, as shown and described.

DESCRIPTION

FIG. 1 is a front perspective view of a sealing element for a vehicle canopy or the like showing the new design;

FIG. 2 is a rear perspective view thereof;

FIG. 3 is a left side elevation view thereof;

FIG. 4 is a right side elevation view thereof;

FIG. 5 is a top plan view thereof;

FIG. 6 is a bottom perspective view thereof;

FIG. 7 is a front elevation view thereof; and,

FIG. 8 is a rear elevation view thereof.
